BUMPER GUARD FOR AN AUTOMOBILE

John E. Schwarz, Oak Park, Mich., assignor to Chrysler Corporation, Highland Park, Mich., a corporation of Delaware

Application June 11, 1956, Serial No. 41,860

Term of patent 7 years

(Cl. D14—6)

Fig. 1 is a front elevational view of a bumper guard for an automobile showing my new design;

Fig. 2 is a plan view thereof;

Fig. 3 is a side elevational view thereof;

Figs. 4 and 5 are sectional views taken on the lines 4—4 and 5—5, respectively, of Fig. 1; and

Fig. 6 is a perspective view of the bumper guard.

I claim:

The ornamental design for a bumper guard for an automobile, substantially as shown.
